UNITED STATES PATENT OFFICE

ALBERT PATITZ, OF MERIDEN, CONNECTICUT, ASSIGNOR TO THE BRADLEY & HUBBARD MANUFACTURING COMPANY, OF SAME PLACE.

DESIGN FOR A LAMP-FOUNT.

SPECIFICATION forming part of Design No. 18,262, dated April 17, 1888.

Application filed February 27, 1888. Serial No. 265,524 Term of patent 7 years.

To all whom it may concern:

Be it known that I, ALBERT PATITZ, of Meriden, in the county of New Haven and State of Connecticut, have invented a new Design for Lamp-Founts; and I do hereby declare the following, when taken in connection with accompanying drawing and the letters of reference marked thereon, to be a full, clear, and exact description of the same, and which said drawing constitutes part of this specification and represents a side view.

This invention relates to a design for the shape and ornamentation of founts for lamps; and it consists in the configuration and ornamentation, as shown in the accompanying illustration.

The fount is represented as composed of an upper and lower section. The lower section is of hemispherical shape, expanding from the center bottom upward to its junction with the upper section. The upper section contracts by an inward curve to a flat upper surface. At the junction of the two sections is the representation of an annular projecting bead, *a*. The surface of the lower section is ornamented by the representation of a series of embossed tongues springing radially from the center bottom and extending up nearly to the annular bead. These tongues are alternately ornamented with the representation of a leaf

springing from the root of the tongue. The upper section is ornamented by a series of similar tongues, which spring from the top and extend downward toward the annular bead, and are alternately ornamented with the representation of a leaf, as shown in the accompanying illustration. The ornamentation of the upper surface may be omitted without departing from this design. The essential feature is the hemispherical shape of the lower section, having upon its surface the representation of a series of tongues springing from the lower center and extending up upon the surface, the tongues alternately ornamented by the representation of a leaf.

I claim—

The design for a lamp-fount the lower section of which is of hemispherical shape and the upper section curved inward, the said lower section having upon its surface the representation of a series of tongues springing from the lower center and extending up upon the surface, the tongues alternately ornamented by the representation of a leaf, as shown in the accompanying illustration.

ALBERT PATITZ.
